Primary Examiner — Susan Bennett Hattan*Assistant Examiner* — Brett Miller(74) *Attorney, Agent, or Firm* — Rankin, Hill & Clark LLP(57) **CLAIM**

The ornamental design for a measuring container, as shown and described.

DESCRIPTION

FIG. 1 is a perspective view of a measuring container; FIG. 2 is a front view thereof;

FIG. 3 is a right side view thereof, the left side being a mirror image;

FIG. 4 is a rear view thereof;

FIG. 5 is a top view thereof; and,

FIG. 6 is a bottom view thereof.

The broken lines depict portions of the measuring container that form no part of the claimed design.

1 Claim, 6 Drawing Sheets(56)
